UNITED STATES PATENT OFFICE.

CHARLES C. PARSONS, OF NEW YORK, N. Y., ASSIGNOR TO HENRY BOWER,
OF PHILADELPHIA, PENNSYLVANIA.

STILL FOR AMMONIA, SPIRITS, &c.

SPECIFICATION forming part of Letters Patent No. 244,399, dated July 19, 1881.

Application filed September 27, 1880. (No model.)

To all whom it may concern:

Be it known that I, CHARLES CHAUNCEY PARSONS, of the city, county, and State of New York, have invented certain new and useful Improvements in Stills for Ammonia, Spirits, &c., of which improvements the following is a specification.

The object of my invention is to provide an effective and economical apparatus for the elimination of volatile bodies from solutions by the action of steam thereon, said apparatus being specially designed for the treatment of gas-liquor in the manufacture of ammoniacal salts, and being also adaptable to use in the distillation of spirits, turpentine, and other liquids.

To this end my improvements consist in sundry novel devices and combinations, embracing a double-chambered body having upper and lower conical-bottomed compartments, a communicating-pipe provided with a cock or valve, and connecting said compartments, a series of steam-supply pipes opening into said compartments, a vertical column communicating with said upper compartment and provided with a series of distributing shelves or trays, and a supply and a discharge pipe.

The improvements claimed are hereinafter fully set forth.

30 In the accompanying drawings, Figure 1 is a vertical central section through a still embodying my improvements. Figs. 2 and 3 are horizontal sections through the same at the lines *x x* and *y y* of Fig. 1 respectively; Figs. 4 and 5, similar sections through the column, showing the arrangement of the distribution-shelves and their supports; Fig. 6, a plan view, on an enlarged scale, of a section of one of the distributing-shelves, and Fig. 7 a view, in elevation and on an enlarged scale, of one of the steam-pipes leading into the upper compartment.

To carry out my invention, I provide a cylindrical body, *A*, of stout sheet or plate metal, divided by a conical diaphragm or partition, *a'*, into an upper compartment, *A'*, and a lower compartment, *A²*, the bottom, *a²*, of the latter being of similar form to the diaphragm *a'*. The upper compartment, *A'*, is connected by a frusto-conical cap, *a*, with the lower end of a

vertical cylindrical column, *A³*, which is closed at top by a cap, *a³*, having an exit or discharge pipe, *a⁴*, connected to its center. The upper and lower chambers are connected by a communicating-pipe, *B*, extending from the center of the diaphragm *a'* to the outside of the body *A*, where it is provided with a suitable cock or valve, *b*; and opening at its lower end into the lower compartment, *A²*, a pipe, *a⁵* having a cock or valve, *a⁶*, is connected to the center of the bottom, *a²*, of the lower compartment, *A²*, and fulfills the function of drawing off waste liquor therefrom, as required. Each of the compartments is provided with a man-hole, *a⁷*, of proper dimensions, and with one or more gage-cocks, *a⁸*, and pipes *a⁹ a¹⁰*, each having a cock, *a¹¹*, communicating with the upper and lower compartments, respectively, to admit of the introduction of milk of lime thereto, as may be required in the treatment of ammoniacal solutions.

Two inlet steam-pipes, *C C*, are connected to the bottom of the lower compartment, at points diametrically opposite each other and about equidistant between its axis and periphery. The inner ends of the pipes *C*, which open into the compartment *A²*, are drawn down to a reduced diameter, so as to form jets or contracted nozzles, which point in opposite directions, as shown in Fig. 2.

80 A series of U-shaped steam-pipes, *C'*, of different lengths, the form of which is clearly shown in Fig. 7, is arranged in line diametrically within the upper compartment, *A*, each pipe having a flange, *c'*, upon its lower end, 85 by which it is secured to the diaphragm *a'*, above and around an opening of corresponding diameter therein, and, after passing upwardly and downwardly in U form, terminating in a horizontal bend, *c²*, at a short distance above 90 its lower flange, *c'*. The bends *c²* of the pipes on one side of the axis of the body point in opposite direction to those of the pipes on the other side, as shown in Fig. 3.

95 A supply-pipe, *D*, for the introduction of liquid to be treated, is led into the column *A³* near its top, terminating in a ring or a series of arms perforated throughout its or their extent, so as to discharge the entering liquid in a series of small streams or jets divided over 100

the transverse area of the column. A series of distributing shelves or trays, D', is arranged within the column between the pipe D and the lower end, being supported upon segmental sections d of angle-iron, secured in pairs, alternating in relative position, so as to break joints to the inside of the column. The function of the shelves or trays D' is to divide and distribute as thoroughly as practicable the streams of liquid fed in through the pipe D and expose the same to the action of upward currents of steam, and a construction which I have found to be desirable, though not essential, is shown in the drawings, each shelf being formed of a series of sections composed of narrow strips of pine board, the surfaces of which are left rough as they come from the saw, the strips of each section being maintained at a distance apart about equal to their own width by intervening end and central blocks, and the strips of the alternate shelves being set relatively at right angles, as shown in Figs. 5 and 6.

In the operation of my invention the gas-liquor or other solution from which volatile constituents are to be extracted is supplied through the pipe D to the column A³, and passes downward in a minutely-divided state through the series of shelves D' into the upper compartment, A', of the body A, encountering in its course currents of steam, which are admitted through the pipes C C into the lower compartment, and thence through the pipes C' to the upper compartment and column, by the action of which steam a portion of the volatile constituents is set free and passes out through the discharge-pipe a⁴ to a proper receptacle. The unseparated solution falls into and is permitted to accumulate to a desired height in the upper compartment, A', where the volatilization is continued by the influence of the currents of steam which boil up through the solution, the operation being facilitated by the agitation and whirling motion communicated thereto by the induction of the steam in reverse direction on each side of the axis of the still-body. After having been subjected to the action of steam in the upper compartment for such period as may be found necessary to readily evolve volatile constituents, the solution is drawn off through the communicating-pipe B into the lower compartment and further similarly treated therein, such of the remaining volatile matter as is susceptible of separation being carried off with the steam through the pipes C', and thence, as before, through the column A³ and out of the upper discharge-pipe thereof. The waste liquor is led off from the lower compartment, as required, by the pipe a⁵. The pipes a⁹ a¹⁰ enable milk of lime to be introduced at the proper period into the solution in the compartment when the apparatus is employed in the manufacture of ammonia from gas-liquor, and may or may not be essential or desirable, according to the character of the solution operated on.

It will be seen that the apparatus affords

facilities for the convenient and thorough application of steam to finely-divided streams or strata of a solution supplied thereto, as well as enables the solution to be thoroughly agitated during the operation, without the necessity of employing power or moving mechanism therefor, and, further, that the exhaustion of the volatile constituent may be continuously and progressively effected, and to as high a degree as is practicable, by the use of steam as a medium.

My improvements are specially advantageous in the treatment of liquids containing solid matters in suspension, as lime in gas-liquor, and grain residues in the distillation of mash, the rotary or whirling motion imparted to the contents of the still by the reversely directed currents of steam preventing the settling of the suspended solid matter, and the conical form of the bottoms, with their central discharges, insuring the removal of the entire contents of the compartments when the charge is drawn off.

I do not herein limit the application of my improvements to a still-body having two chambers or compartments only, as described and shown, for the reason that a greater number may in some cases be desirable, and may be employed without departing from the spirit of my invention. I have, further, for convenience of illustration and description, in this instance set forth the several compartments as constituting divisions of a single body, placed vertically one above another; but it will be obvious that, if desired, said compartments may be set at different levels in different vertical planes, the latter construction, which enables the height of the apparatus to be correspondingly reduced, being conveniently applicable in locations in which restricted head-room would preclude the arrangement of the compartments in line vertically.

I am aware that double-chambered vessels having compartments connected by a valved pipe, to which compartments steam is admitted, and which communicate with vertical condensing columns provided with perforated partitions, are not new in distilling apparatus, and I do not therefore broadly claim said devices, either singly or combined.

I claim as my invention and desire to secure by Letters Patent—

1. In an apparatus for separating volatile constituents from solutions, the combination, substantially as set forth, of two conical-bottomed chambers or compartments, located one above the other, a valved communicating-pipe connected centrally to the bottom of the upper compartment and leading therefrom into the lower, and series of steam-pipes leading into each of said compartments.

2. In an apparatus for separating volatile constituents from solutions, the combination, substantially as set forth, of a body having a cylindrical conical-bottomed compartment, and a series of steam-pipes opening into said

compartment and having their discharge orifices turned in opposite directions upon opposite sides of the axis thereof.

3. In an apparatus for separating volatile constituents from solutions, the combination, substantially as set forth, of two or more cylindrical conical-bottomed compartments, steam-pipes opening into the lower compartment, and having contracted nozzles turned in opposite directions upon opposite sides of the axis thereof, and a series of steam-pipes each of which leads into one of the upper compartments from the compartment next below it, said pipes terminating in discharge-orifices which are turned in opposite directions upon opposite sides of the axis of the compartment.

4. In an apparatus for separating volatile constituents from solutions, the combination, substantially as set forth, of two or more conical-bottomed chambers or compartments, a valved communicating pipe or pipes connect-

ing said compartments, a series of steam-pipes opening into said compartments, a vertical column communicating at bottom with the upper compartment, a series of distributing shelves or gratings arranged vertically one above the other in said column, and supply and discharge pipes communicating with said column at or adjacent to its top.

5. In an apparatus for separating volatile constituents from solutions, the combination, substantially as set forth, of a body, a column communicating therewith, and a series of distributing-shelves each of which is composed of wooden strips separated by blocks, said shelves being disposed within the column with their strips alternately at right angles.

CHARLES CHAUNCY PARSONS.
